UNITED STATES PATENT OFFICE.

BERNHARD F. ZILISCH, OF WATERTOWN, WISCONSIN.

CLOTHESLINE SUPPORT.

Application filed February 9, 1923. Serial No. 617,907.

To all whom it may concern:

Be it known that I, BERNHARD F. ZILISCH, a citizen of the United States, and resident of Watertown, in the county of Jefferson and State of Wisconsin, have invented certain new and useful Improvements in Clothesline Supports; and I do hereby declare that the following is a full, clear, and exact description thereof.

10 The invention comprises a horizontal framework for carrying stretches of clothes line and supports for the framework, each of the supports being received in a socket in a concrete foundation, and the portions 15 of the framework being separable from the supports and from each other.

A primary object of the invention is the provision of a strong, durable, and simple clothes line frame, which facilitates stringing of the clothes line and supports the line. The frame work and supports are such as are adapted to carry a very considerable weight, and the tubular supports are rigidly maintained in their sockets without danger 25 of collapse.

An object of the invention is the provision of a structure, the parts of which may be readily assembled. Thirteen pipe sections are provided, including the tubular supports. The supports are capable of rapid insertion into the sockets provided therefor. The braces which make up the framework are readily positioned, convenient engaging joints being provided for this purpose. The 30 parts are comparatively light in weight, and the efforts of only one person are required in assembly. Similarly, the structure may be taken down, the joints being such as to facilitate this connection.

40 An object of the invention is the provision of a structure adapted to be covered with rugs and to support the rugs without danger of damage thereto, there being no projecting knobs or other parts of a kind adapted to cause damage. This construction facilitates the usage of the device as a summer house, the framework being covered suitably.

An object of the invention is the provision 50 of a framework, adapted to be lowered from

a high position in which they brace the structure, to a comparatively low horizontal position, wherein they may be used as a support for a mattress, planks being provided extending from one brace member to 55 the other. If desired, the brace members in their lowered position may serve as a bench.

With the above and other objects in view, which will appear as the description proceeds, the invention resides in the novel construction, combination and arrangement of parts substantially as hereinafter described and more particularly defined by the appended claims, it being understood that 60 such changes in the precise embodiment of the herein disclosed invention may be made as come within the scope of the claims.

In the accompanying drawing is illustrated one complete example of the physical 70 embodiment of the present invention constructed according to the best mode so far devised for the practical application of the principles thereof.

Figure 1 is a perspective view of the supports in their assembled position. 75

Figure 2 is an elevation of a middle support, showing a longitudinal bracing section and a portion of a transverse brace.

Figure 3 is a section on the line 3—3 of 80 Figure 2.

Figure 4 is a section on the line 4—4 of Figure 1.

Figure 5 is a section on the line 5—5 of 85 Figure 4.

Figure 6 is a section on the line 6—6 of Figure 4.

Figure 7 is a detailed end view of a longitudinal brace.

Tubular supports 10, 11 and 12 are provided arranged in alignment, and similar aligned supports 10', 11' and 12' are provided. Supports 10—10', and 12—12' are at the corners of an imaginary rectangel. 90

The supports 10 10' and 12 12' are preferably spaced quite a ways apart and an intermediate pair of supports 11 and 11' are provided, as shown in Figure 1,—the support 11 aligning with supports 10 and 12 and the supports 11' aligning with supports 100

10' and 12'. The supports 10 and 10' are joined by a transverse brace 13 and the supports 12 and 12' are joined by a transverse brace 17. These end transverse braces are respectively provided with hooks 14 and 18 which are regularly spaced along such braces. The supports 11 and 11' are provided with an intermediate transverse brace 15. This transverse brace carries a plurality of retainers which align with the respective hooks 14 and 18. Each of these retainers or guiding means is formed of a pair of upstanding ears 16 and 16' (see Figure 2) which are spaced a slight distance apart, and which converge so as to provide a contacted upper entrance throat therebetween. It is intended that a plurality of stretches of clothes lines be strung between successive pairs of hooks 14 and 18 and that the intermediate portion of these clothes lines be received between the ears 16 and 16' of the retainers on the intermediate brace 15. Longitudinal brace 19, extends between supports 10 and 11. Brace 20 extends between supports 11 and 12. A brace 19' extends between supports 10' and 11' and a brace 20' extends between supports 11' and 12'. A concrete foundation 21 is provided, having spaced socket members 22 therein, a socket member being provided for each of the supports, snugly receiving the end of the support, which is limited in downward movement by collar 23. The supports are thus securely mounted in position and the cooperative relationship of the supports and braces is such as to provide a secure and rigid framework, adapted to sustain a very considerable weight, to which the clothes line might be subjected.

40 Threaded on support 10' is a ferrule 24, having a pair of keyhole openings thereon, spaced substantially 90 degrees apart. Threaded in brace 13 is a plug 25, having a shoulder 26, contacting with the end of the brace. The plug is insertable thru one of the keyhole openings of ferrule 24, and is provided with a lateral projecting finger 27. Support 10 is provided with a similar plug to plug 25. In assembling the braces 13, the plug on one end is inserted into one of the ferrules 24 and 28. Then the plug at the other end is inserted in an opening in the other ferrule. The openings are of keyhole shape and permit insertion of the fingers 27. After the ends of the plugs have been inserted, the brace is rotated so as to bring the finger 27 in contact with the inner cylindrical surface of the ferrule. The contact of the shoulder 26, with the exterior of the ferrule limits the rotation of the brace, so that the hooks 14 are maintained in substantially horizontal position.

45 Brace 17 is assembled with supports 12-12' in the same manner as brace 13.

50 Supports 11-11' are provided with fer-

rules 29-29' respectively. Each of the ferrules has three keyhole openings therein. Brace 15 has at each end thereof a plug 30, provided with a shoulder 31 and a reduced neck 32, having straight sides. The brace 70 is assembled by inserting one of the plugs into the larger portion of the keyhole opening, then directing the other plug into the opposite opening and moving the brace downwardly, so that the neck 32 is gripped 75 in the narrow portion of the keyhole.

Brace 19 is provided at one end with a plug 33, similar to plug 30. Brace 19' is similarly provided. A plug 34, similar to block 25, projects from one end of brace 19' 80 into ferrule 24. Brace 19 is carried by support 10. Brace 20 is carried by support 12 and brace 20' is carried by support 12' in the manner in which brace 19' is carried by support 10'. Brace 19' is removably attached with respect to ferrules 24 and 29' by inserting plug 34 into the opening in ferrule 24, then by rotating the brace until the finger 35, carried by the plug, contacts with the inner surface of the ferrule. A plug on 90 the other end of brace 19' is then inserted into the opening in ferrule 29' and urged downwardly, so as to position the neck of the plug in the narrow portion of the opening. The brace is thus prevented from rotation and is incapable of release from ferrule 24 with which it is securely locked. The manner of locking is such as to effectually eliminate all danger of collapse of the structure, so that it is maintained rigidly in place. 100

Support 11 is provided with an opening 36 spaced slightly above the foundation 21. Supports 10-10' and 11' are provided each with a similar opening. Brace 19 may be readily removed from ferrules 28 and 29, 105 and positioned in the lower openings in supports 10 and 11. Similarly, brace 19' may be lowered. The arrangement of supports in the lowered position is indicated in dotted lines in Figure 1. Planks 37 and 38 110 may be extended between the braces 19-19' for supporting a mattress 39, or if desired, the braces may be made to serve as a bench.

Ferrule 24 and each of the other ferrules is rounded slightly at the top and projects 115 only a short distance upwardly beyond the braces, so that rugs may be drawn over the framework without danger of damage to them, as there are no projecting parts of such nature as to cause danger of tearing the 120 fabric. The framework may be suitably covered and is then adapted to serve as a summer house.

I claim:

A device of the class described comprising 125 a plurality of spaced socket members, a plurality of vertical supports slidably carried by said socket members and arranged in laterally spaced pairs and comprising end pairs and an intermediate pair, transverse 130

and longitudinal braces detachably joining the upper portions of adjacent supports and including end transverse braces and an intermediate transverse brace, a plurality of attaching members carried by the end transverse braces and adapted to receive the ends of clothes lines, and a plurality of line guid-

ing members carried by said intermediate transverse brace.

In testimony that I claim the foregoing I have hereunto set my hand at Watertown, in the county of Jefferson, and State of Wisconsin.

BERNHARD F. ZILISCH.
